UNITED STATES PATENT OFFICE.

FRANK C. ROZYCKI, OF PHILADELPHIA, PENNSYLVANIA.

KEYLESS PADLOCK.

Application filed September 14, 1920. Serial No. 410,201.

To all whom it may concern:

Be it known that I, FRANK C. ROZYCKI, a citizen of Poland, residing at Philadelphia, in the county of Philadelphia and State of Pennsylvania, have invented certain new and useful Improvements in Keyless Padlocks, of which the following is a specification.

This invention relates in general to locks and in particular to padlocks of the keyless type.

The principal object is to provide an improved padlock structure adaptable for all purposes where a lock of the shackle variety is employed.

An additional object is to provide a lock structure having a casing with which the shackles of various lengths may be employed and insertable at any end of the casing, suitable permutation means being employed for locking the shackle to the casing.

With the above and other objects in view, the invention may be said to reside generally in the details of construction, combination and arrangement of parts as will be hereinafter more fully pointed out, reference being had to the accompanying drawings, wherein

Figure 1 is a side elevation of the improved shackle and lock casing.

Figure 2 is a top plan view of the casing. Figure 3 is an end view thereof.

Figures 4 and 5 sectional views of the casing disclosing the arrangement of the locking studs.

Figure 6 is a plan view of a long arm shackle and

Figure 7 is a perspective view of the lock casing partly in section to illustrate the arrangement of the passageways and stud holes.

The casing of the lock is preferably formed of a solid block, indicated at 1 and provided with vertically and horizontally disposed passageways 2 and 3, extending entirely through the block. The passageways are arranged in pairs, running from corresponding edge faces of the block, the openings of each pair intersecting the opening of the other pair, interiorly of the block as indicated at 4. A stud hole 5 is drilled crosswise to the block at the point of intersection of the passageways and communicating with both passageways, as shown in Fig. 7. Inserted in each hole 5 is a lock stud 6 having a shoulder or head 7 for abutment against one side of the block and a reduced

shank portion 8 fitting into a recess formed in the inner face of a knob or button 9. Each stud is notched on one side as at 10, in conformity with the shape of the passageway and may be brought to align with the wall of either passage upon turning knob 9 in the proper direction.

Stamped or otherwise formed upon an outside face of the block casing 1 and surrounding each knob is a dial face 11 suitably numbered as indicated to advantage in Figure 1 of the drawing. Any indicating means such as an arrow, may be stamped or otherwise formed upon the front face of each button for registering with any of the numbers of a surrounding dial face to facilitate the unlocking of the device in conformity with the numbers of the combination.

In the use of the device for ordinary locking purposes, a short arm shackle 13 can be employed and is notched along the arm as at 14, the notches being spaced to correspond with the spacing of the intersecting passageways of the casing block. In Figure 6 is illustrated a long armed shackle, the arms of which are provided with a plurality of notches 16 arranged in closely spaced relation and extending practically throughout the length of the arms. This type of shackle is designed for use when the lock is employed in connection with automobiles, for locking the steering wheel or the brake and gear levers. It may also be used generally where a padlock is desired.

Regardless of whichever type of shackle is used, the arms of the same are insertable through the passageways of the block from either of the four edges to which the passageways extend and are designed to be firmly locked against movement upon proper manipulation of the locking studs 6.

The letters A, B, C and D on the face of the lock indicate the various edges or sides through which the shackle may be inserted and the operation of the device, assuming that the shackle is to be inserted through edge A, the studs 6 are each turned with their notched portions registering with vertical passages 2, as illustrated at the left of Figure 4, thereby making a clear passage for the arms of the shackle. Though all of the studs are in a corresponding position with respect to the passageways, the arrows of the knob point to different dial numbers in accordance with the particular number of the combination assigned to each lock.

stud. For instance, the combination in the first instance, reading the dial from left to right is 11, 1, 3 and 6. The shackle is now inserted in the casing so that the notches 14 of the arm come directly opposite the locking studs 6 which are then turned by means of knobs 9 threaded thereon. This causes an unnotched portion of each stud to enter the notch of the shackle arm, preventing the latter from moving upwardly or downwardly or in any manner being disengaged from the lock casing. To open the lock, the knobs are turned to the designated points, which brings the notched portions into alignment with the shackle arms, preventing the withdrawal of the latter. In order to effect a change in the combination, the shackle may be inserted into the casing from the lower opposite side or edge B which will reverse the position of the lock casing, causing the last dial operated in the previous combination to be now the first operated in the new combination. The combination is merely reversed the numbers merely reading backwards, namely 6, 3, 1 and 11. It will thus be seen that the same set of numbers employed in both combinations and that the order of their reading is dependent upon the position of the block with respect to the shackle.

Upon inserting the shackle through either side C or D the combination number of each dial E and F and G and H would be correspondingly read. That is to say the combination for side C reading the dial from left to right would therefore be 12—2, 9 and 10, the inverse order of the numbers for example, 10, 9, 2, 12 forming the combination for the opposite edge D. In order to permit the withdraw of the shackle from either edge of the lock casing, it is necessary that the knob be turned with the arrows pointing to the proper numbers so that the notched portion of the locking studs will be properly aligned with the right passageways. There are thus two sets of different numbers which go to make up four different combinations, one for unlocking each shackle at each edge of the block.

It is believed that the advantages of the novel arrangement of the locking studs and shackle passages will be readily appreciated and understood from the foregoing description when taken in connection with the accompanying drawings.

Having thus fully described my invention what I claim as new and desire to secure by Letters Patent is:—

1. A lock comprising a lock casing having intersecting passageways, a shackle insertible into the casing through any end of the passageways, and means for locking the shackle to the casing. 60

2. A lock comprising a lock casing having intersecting passageways, a shackle insertible into the casing through any end of the passageways, and rotatable means adjacent the ends of these passages for holding the shackle against removal. 65

3. A lock comprising a casing having intersecting passageways formed therethrough, a shackle insertible into any of the passageways, and means at the intersection of the passageways for locking the shackle against removal. 70

4. A lock comprising a casing having intersecting passageways, a shackle insertible into the casing through any end of the passageways, said shackle having notched arms to correspond with the passageways and means at the intersection of the passageways engaging the notched arms for locking the shackle against removal. 75

5. A lock comprising a casing having intersecting passageways, a shackle insertible into the casing through any end of the passageways, said shackle having notched arms to correspond with the passageways, and rotatable notched elements at the intersection of the passageways engaging the notched arms for locking the shackle against removal. 85

6. A lock comprising a casing having intersecting passageways, a U-shaped shackle insertible into the casing through any end of the passageways, said shackle having notches on the major portion of the arms thereof to correspond with the passageways when said shackle is moved to different positions, and rotatable, notched studs at the intersection of the passageways engaging the notched arms for locking the shackle against removal. 90

In testimony whereof I affix my signature in presence of two witnesses.

FRANK C. ROZYCKI.
